UNITED STATES PATENT OFFICE.

BEN B. STROPE, OF COSHOCTON, OHIO, ASSIGNOR TO THE STANDARD ADVERTISING COMPANY, OF SAME PLACE.

DESIGN FOR A GLASS-HOLDING TRAY.

SPECIFICATION forming part of Design No. 32,950, dated July 17, 1900.

Application filed June 18, 1900. Serial No. 20,769. Term of patent 31 years.

To all whom it may concern:

Be it known that I, BEN B. STROPE, a citizen of the United States, residing at Coshocton, in the county of Coshocton and State of Ohio, have invented and produced a new and original Design for a Glass-Holding Tray, of which the following is a specification.

This invention relates to a new and original design for a glass-holding tray; and it has o for its object to provide a design of this character which shall be both useful and ornamental.

The leading feature of the design resides in a dished body having an upwardly-flaring rim 5 and a flat bottom, the latter being provided with a circular series of spaced radially-disposed rounded ribs projecting above the plane of the bottom and radiating from near the center to the rim thereof.

o The minor features of the design are the radially-disposed upstanding ribs, being concavo-convex in cross-section, and the upwardly-flaring rim, being provided with a curved peripheral edge.

5 An additional minor feature of the design is the bottom of the tray, being provided upon the upper surface thereof with a circular series of representations of bottles alternating with the radial ribs or rib projections.

o In the drawings, Figure 1 is a perspective view of a glass-holding tray embodying the herein-described design. Fig. 2 is a bottom

perspective view. Fig. 3 is a vertical cross-sectional view of the tray.

Referring particularly to the drawings, the 35 numeral 1 designates the tray, essentially consisting of a circular dished body having an upwardly-flared rim 2 and a flat bottom 3. The upwardly-flared rim 2 is provided with a curved peripheral edge 4, and the bottom 3 is 40 provided with a circular series of upstanding concavo-convex ribs 5. The said ribs 5 are arranged in regular spaced relation and project above the plane of the bottom, and said ribs also radiate from near the center of the 45 bottom to the rim thereof.

In addition to the circular series of radially-disposed rounded ribs 5 the flat bottom 3 of the tray-body is provided upon the upper surface thereof with a circular series of representations of beer-bottles, which alternate with the radial ribs 5 and have their necks disposed toward the center of the body. 50

What is claimed is—

The design for a glass-holding tray herein 55 shown and described.

In testimony that I claim the foregoing as my own I have hereto affixed my signature in the presence of two witnesses.

BEN B. STROPE.
